COMBINED ELECTRIC WIRING AND
MOLDING SYSTEM

Robert L. Davison, New York, N. Y., assignor to
John E. Pierce Foundation, New York, N. Y.,
a corporation of New York

Application September 23, 1933, Serial No. 690,653

2 Claims. (Cl. 173—334.1)

This invention relates to a system of combined electrical wiring and molding, serving dual purposes of a finish for a structure of a room, enclosure and the like, as, for example, between 5 the floor and the base board, at the tip of the base board, a picture molding, side wall and ceiling meeting molding, etc., and to house, insulate and protect electrical wiring.

A feature of the present form of my invention 10 is the provision of relatively long units of combined molding and electrical wiring, the terminals of the conductors of such long units not projecting at either end, and advantageously substantially flush at both ends of each long unit, in 15 association with units of relatively short length, the terminals of the conductors of each short length projecting at both ends of each short unit, each short unit serving to interconnect long units, the terminals of the respective conductors 20 being spaced and dimensioned relative to one another to effect mechanical as well as electrical connection between the corresponding conductors of the thus assembled units.

A primary feature of the present invention is 25 the provision of outlet means afforded by the short and/or long units of my system, the channels of each outlet means being initially concealed.

Advantageously, such object is attained by 30 providing such outlet means in a short unit, and coating or facing the exposed face of the unit with a frangible material to thus conceal the channels of the outlet means, whereby upon locating the terminals of a plug of an electrical cord 35 or other wiring and applying pressure upon the areas of the thus initially concealed ends of the channels, such areas of the frangible material are removed, enabling the terminals of the plug to be brought into good electrical engagement with 40 the contact members of the outlet means, and accordingly with the respective conductors of the unit.

Such form of initially concealed outlet channel 45 arrangement may be carried out in the construction of long units at standard or other spacial relation with one another.

Preferably, the locations of the frangible or 50 other removable areas of the initially concealed outlet channels may be identified by projectional, indentational or other indications.

A feature of the present invention is the desideratum of the assembled component units of my system having substantially like, and preferably identical, outward appearance, attained, for 55 example, by providing substantially identical con-

figuration, color, etc., of the exposed faces, whereby the component units, inclusive of its outlet means provisions, present visually substantial integrity.

To afford a suitable outlet means, singly or 5 plurally, for electrical connection with the desired electrical consumption device, or devices, such as electric lamps, electric clocks, radios, electrical refrigerators, etc., the units of my system are mechanically assembled to locate such 10 outlet means—provided unit or units closely adjacent the location or locations of the respective consumption devices.

Desirably, the material of the body of each 15 unit is of electrical insulating quality. The positioning of the respective conductors in the units and insulatingly embodying of the same within the body material may be carried out by molding, extruding, or such other procedure as may be preferred.

The frangible concealing outer material of the 20 outlet means—provided short unit may be formed by dipping or other application, molding, etc. The relatively short dimensions of the short unit facilitates the procedure, attendant also with 25 low material and labor costs.

Advantageously, the outer face of each unit 30 may serve as a finish material, which may be readily applied by dipping or other application, whereby the outer ends of the channels of the outlet means are closed by a thickness of the 35 finish material of such small dimensions as to render the same readily frangible for the insertion of the terminals of a plug or equivalent.

In such preferred embodiments of my invention 40 the frangible material extends imperforately over the channels of the outlet means, and presents identical appearance to the eye of the observer as the remainder of the exposed faces of the unit and of the exposed faces of adjacent units.

Advantageously, the conductors of the long 45 units of my molding-electrical wiring system are of tubular or equivalent formation and the conductors of each short unit are of rod or equivalent 50 formation, as is set forth more particularly in my co-pending application Serial No. 682,757, filed July 29, 1933, entitled Electrical wiring and molding system.

If desired, the rod or equivalent form of conductors may be embodied in the long units, in which instance the terminals of both conductors project at both ends of each long unit, and correspondingly the conductors of the short units 55 may be of tubular or equivalent formation, the

terminals of which at both ends of each short unit do not project, and are preferably substantially flush, relative to the respective ends of each short unit, as is set forth and claimed in my co-pending application Serial No. 643,325, filed Nov. 19, 1932, entitled Combined molding and electric conductor.

Further features and objects of the invention will be more fully understood from the following detail description and the accompanying drawing, in which

Fig. 1 is a perspective view, of diagrammatic character, showing one manner of application of my combined molding-wiring system to a reversely angled corner of a room;

Fig. 2 is a perspective exploded view of component units of my combined molding-wiring system, corresponding to units indicated in Fig. 1, on an enlarged scale;

Fig. 3 is a perspective view of a type of corner interconnecting short unit;

Fig. 4 is a vertical central sectional elevation of the short unit illustrated at the left in Fig. 2;

Fig. 5 is a plan view, partly broken away in section, showing a manner of application of a corner short unit assembled with alternately disposed long units; this view also shows another type of long unit;

Fig. 6 is a vertical central sectional view of a short or long unit showing a manner of connection with a power line.

Fig. 1 illustrates a manner of assembly of component units of my combined molding and wiring system, applied to a baseboard, extending about a reversely angled corner of a room. It will be understood that such application is clearly illustrative, and that my system is not limited to the indicated detail construction.

In general, the units of my system comprise relatively long units and relatively short units. The relatively short units serve the general purpose of mechanically interconnecting the relatively long units. Electrical conductors are insulatedly embodied in each of the units, respective conductor termini of the respective units being constructed and located to effect registry. Accordingly, the respective units serve to interconnect one another mechanically as well as to respectively electrically connect the component parts of the respective conductors embodied in the interconnected units.

As above indicated, either of the forms of conductors and arrangement of mechanical-electrical assembly of the same, pursuant to my two stated co-pending applications, may be employed. The form of conductors and arrangement set forth in my aforesaid co-pending application Serial No. 682,757 is preferred, by reason of the mere operation of severing of the material of a long unit to meet varied dimensional requirements in practice attains also a severing of the embedded tubular conductors, flush, or substantially flush, with the severed end of the unit. In such embodiment of my invention, each short unit is provided with rods or equivalent serving as the conductors, to afford joint mechanical and electrical connections with the projecting ends of the tubular or equivalent conductors of the long unit or units.

The long units indicated in Fig. 1 are designated 10; the short units of rectilinear formation, that is to say, serving to interconnect long units in "straight runs", are designated 11. The converging facial short unit indicated at 12 serves to interconnect the indicated alternately disposed

long units 10, 10 at the convergent angle between the indicated walls 13, 14. The divergent short unit 15 serves to interconnect the indicated alternately disposed long units 10, 10, at the divergent angle between the indicated walls 13, 16.

A characteristic of the present invention resides in the employment of short units, each of which is provided with suitable outlet means, including channels for the contact members of the outlet means, the channels at their respective intersections with the exposed face of the molding being initially closed by suitable frangible material or other removable means.

One embodiment of my invention is indicated in Fig. 2 wherein the short unit 11 is provided with rod or equivalent conductors 17, 18, the respective ends 17a, 18a of the conductors 17, 18, projecting at both ends of the unit 11. Within the unit, as indicated in Fig. 4, I provide suitable outlet means, comprising in essence the channels 19, 20 within which are positioned resilient or other suitable contact members 21, 22 respectively secured and electrically connected to the conductors 17, 18.

As above indicated, the material of the body 11a of the unit 11 is preferably of insulating character, to thereby directly insulate the bared conductors 17, 18, and also to serve as appropriate body material for the molding per se. The exposed face 11b of the unit, and in particular of the portions 11c located at the respective otherwise exposed ends of the channels 19, 20, is of a material having suitable qualities to serve as an appropriate finish for the exposed face 11b, and of sufficient frangible character whereby upon approximately positioning the terminals of a plug at the areas of the material portions 11c, 11c and applying pressure inwardly relative to the unit 11, the portions 11c, 11c, are broken, and removed, thus enabling the plug terminals to be received within the respective channels 19, 20, and to engage the contact members 21, 22 to make good electrical contact therewith.

As suitable material 11c, I cite lacquers, varnishes, heavy shellacs, rubber inclusive of latex compositions, etc.

The long unit 10 shown in Fig. 2, illustrates the employment of tubular or equivalent conductors 23, 24 embodied in the material serving as the body 10a of the unit, the conductors 23, 24 being insulatedly embedded therein and positioned relative to one another and relative to the projecting termini 17a, 18a of the respective conductors of the therewith connected short unit 11.

The respective termini 23a, 24a, at both ends of the long unit 10 are flush, or substantially flush with the respective ends of the body of the unit.

The long units 10 may be manufactured of standard length, and/or of such range of lengths as may be desired. For attaining lengths less than any standard or other length of a long unit 10, mere sawing operation or other severing of the material accomplishes the reduction of length and also rendering the conductor termini 23a, 24a flush, or substantially flush, with the severed end of the unit.

Desirably, the exposed faces of the long units and of the short units are substantially in replica of one another, inclusive of configuration, surface texture, color, etc. In the attainment of such result, the exterior face of each long unit 10 may be coated with the same or like finish mate-

rial serving as the initially closing material 11c of the short units.

Fig. 3 illustrates a type of convergent facial short unit 12, its conductors 17, 18, being bent, preferably arcuately as illustrated, in accordance with the angle of its converging faces, in this instance, a right angle. It will be understood that for angular short units other than a right angle, the exposed faces may be angled correspondingly, and that the bend of the embodied conductors 17, 18, may also correspond with such other angle.

Suitable connection with the house wiring system or other power line wires is had as will be understood by those skilled in the art. Advantageously, as is illustrated in Fig. 6, such power connection is afforded by the provision of a rearwardly disposed recess, to thereby both conceal and protect the power line connections. Most advantageously, power connection is had by providing all, or mayhap special types, of short units 11 with such rearwardly disposed recess, indicated in Fig. 6, at 25, the bared ends of the leads 26, 27 of the cable 28 being soldered or otherwise secured to the indicated conductors 17, 18 of the combined molding-wiring unit 11, pursuant to approved practice; the recess 25 is preferably closed by the use of a suitable plastic insulating material, in protection of the secured connections.

The use of frangible or other removable form of initial concealment of the outlet means may be carried out in the manufacture of long units, by single or plural outlet means for each long unit, at predetermined or other longitudinal spacing relative to one another as may be preferred. Fig. 5 illustrates one form of such embodiment of my invention, the facial portions 29, 30 at the indicated dotted areas, being of the nature of the facial material portions 11c, 11c, as in a short unit 11, and serving to initially conceal the respective channels of a suitable outlet means, similarly as is indicated in Fig. 4 with reference to a short unit 11.

My invention is similarly applicable to the various other forms of short and long units, as illustrated and/or described in my co-pending application Serial No. 682,757, in each instance the openings of the channels of the outlets provided in the units being initially concealed by frangible or other removable means.

Whereas I have described my invention by reference to specific forms thereof, it will be

understood that many changes and modifications may be made without departing from the spirit of the invention.

I claim:

1. A combined molding and electrical wiring system comprising alternately assembled long and short conductor carrying units composed entirely of insulating material, and adapted to serve as a building molding, hollow electrical conductors insulatedly embodied in each long unit 10 having termini respectively substantially flush at each end of each long unit, said short units serving as couplings for the long units and having electrical conductors insulatedly embodied therein having termini respectively projecting at 15 each end of each short unit and arranged to respectively engage the hollow termini of the conductors of adjacent long units, certain of said short units being provided with outlet means, the exposed faces of said long units and certain of 20 said outlet-provided short units being covered respectively with identical finish material of relatively thin dimension substantially identical in facial contour to effect visual continuity when assembled, such finish material extending continuously over the openings of the outlet means of said outlet-provided short units normally concealing such openings and frangible to afford access into such openings.

2. A combined molding and electrical wiring 30 system comprising alternately assembled long and short conductor carrying units composed entirely of insulating material, and adapted to serve as a building molding, said short units serving as couplings for the long units, the conductors of said long units and said short units being in continuous conductive relationship when the units are assembled end to end, the insulation within the body of each long unit and each short unit wholly embracing the respective conductors 40 of such unit and integrally extending from conductor to conductor of such unit, the exposed faces of said long units and said short units being covered respectively with identical finish material of relatively thin dimension and having 45 their lateral edges in rectilinear alignment to effect visual continuity when assembled, such finish material extending continuously over the openings of said units normally concealing such openings and frangible to afford access into such 50 openings.

ROBERT L. DAVISON.
